FIG. 1.

FIG. 2.

WILBUR H. ARMACOST

INVENTOR

BY *O. H. Thiele*

ATTORNEY

UNITED STATES PATENT OFFICE

WILBUR H. ARMACOST, OF NEW YORK, N. Y., ASSIGNOR TO THE SUPERHEATER COMPANY, OF NEW YORK, N. Y.

SUPERHEATER

Application filed March 19, 1929. Serial No. 348,205.

My invention relates to superheater boilers and has for its principal object the provision of an improved form of superheater which may be readily modified to meet changes in superheating requirements caused by a change in the pressure or capacity at which the boiler is operated.

In order to anticipate future and greater demands on power plant installations, it is becoming increasingly common when installing new equipment to install boilers capable of operating either at greater capacity or pressure, or both, than the immediate requirements of the plant call for, with the end in view of subsequently increasing either the boiler pressure or rating, or both, as the demands for steam increase. It is obviously desirable to run the boiler and superheater at maximum efficiency, both as originally installed and as later modified, and in order to accomplish this purpose, it is necessary to considerably modify the superheater if the boiler operating pressure or rating is materially changed.

Heretofore such procedure has necessitated the rebuilding or replacing of the original superheater installed and the present invention contemplates the elimination of this undesirable requirement by the provision of a novel form of superheater, which will operate efficiently with the boiler as originally installed and which, in case change is made in the boiler operating rate or pressure, may be modified at the minimum expense and in a manner which utilizes, in the modified form, all or substantially all of the original superheater.

The manner in which the invention is carried into effect may best be understood from a consideration of the following detailed description of an illustrative embodiment thereof, shown in the accompanying drawings, in which Fig. 1 is a vertical section through a typical interdeck, cross drum boiler, with the superheater as originally installed in accordance with my invention, and Fig. 2 is a fragmentary vertical section taken through the superheater as modified.

Referring now to Fig. 1, the boiler illustrated is of the conventional form comprising

spaced banks of generating tubes 1 and 2 supplied with water from the steam and water drum 3 through the connecting nipples 4 and 5 and headers 6 and 7. Steam and water discharged from the generating tubes are carried through the uptake headers 8 and 9, nipples 10 and circulators 11 to the drum 3. In the particular form of boiler shown, baffles 12 and 13 serve to direct the combustion gases transversely over the generating tubes.

The superheater comprises an inlet header 14 connected to the steam space of drum 3 by means of pipe 15, an outlet header 16 and a plurality of relatively long tubular superheating units 17. In the form shown the superheating units 17 are composed of a plurality of integrally joined loops with the inlet end of the units connected to header 14. As will be noted, the superheater units 17 occupy only a portion of the space 18 between tube banks 1 and 2 and the outlet ends of these units are spaced from the superheater outlet header 16. Short auxiliary tubes 19 serve to connect the outlet ends of the units 17 with the header 16.

In some instances the ends 17a of the superheater units may be initially bent so that they can be connected directly to the header 16, but the use of the auxiliary short tubes 19 is to be preferred for a reason explained later.

While the specific manner of securing the units to the headers and to each other is not germane to the invention, detachable connections are highly desirable in order to secure the maximum benefit from its use, and the joints are preferably made in accordance with the disclosures in U. S. Patents #1,363,713 and #1,610,741, granted to Benjamin Broido on December 28, 1920 and December 14, 1926 respectively.

By way of illustrating the manner in which the invention may be utilized, let it be assumed, for example, that the boiler as originally installed is capable of operating at 400 lb. per sq. in. pressure absolute, but that for use in supplying steam to an existing turbine, it is to be operated at only 250 lb. per sq. in. pressure absolute and at a given rating. This means that saturated steam at 401 deg. F. will be supplied to the superheater and assum-

ing that 100 deg. of superheat is required, it is found that a three-loop superheater, as shown in Fig. 1, will provide sufficient heating surface to raise the required amount of steam from 401 deg. F. to 501 deg. F. under the furnace conditions obtaining in the boiler.

Let us now assume that the power plant is enlarged by the addition of a turbine designed to operate at 400 lb. per sq. in. pressure absolute and with steam having 150 deg. of superheat. It will be quite obvious that under the new conditions, the boiler designed to operate at 400 lb. can supply steam to the new turbine but only if the superheater is redesigned to provide additional heating surface, as the superheater under the new conditions will be required not only to impart more than 100 deg. of superheat, but it must also impart this additional superheat to saturated steam which reaches the superheater at the saturation temperature corresponding to 400 lb. pressure; that is to say, at 444.8 deg. F. Let us say that it is found that a five-loop superheater is required to provide the necessary heating surface to meet the new requirements.

Assuming that the original superheater has been built as shown in Fig. 1, the additional heating surface required may be readily obtained by removing the auxiliary tubes 19 and connecting in their stead an equal number of two-loop superheater units 17', which occupy the space between the original units 17 and the tube bank 1.

If the units 17 of the original superheater have been connected directly to both headers, the joints between one header and the units may be broken, and the ends 17a of the latter bent to the position shown in Figs. 1 and 2 of the drawings, the additional units 17' being installed as shown in Fig. 2. Obviously, the form of original superheater shown in Fig. 1 provides a more readily convertible device, as it calls for no change whatever in the original units after they are once installed, although a change in the superheater does require the discarding of some or all of the tubes 19.

Obviously, the number of units 17 that may be lengthened at any one time by units 17' in order to meet new conditions is not fixed and the superheater as modified may, for example, consist of a certain number of three-loop units interspersed with a number of five-loop units such as shown in Fig. 2. It will further be evident that the use of joints of the new type shown in the Broido patents hereinbefore mentioned is to be desired as in such event any modifications of the superheater may be effected with the minimum expenditure of time, effort and cost.

As will be appreciated by those skilled in the art, the advantageous application of the invention is not limited to any specific form

of superheater or boiler arrangement. The exemplary form herein disclosed is therefore to be taken as illustrative only and the invention is to be understood as embracing all such forms and modifications of the apparatus as may fall within the scope of the appended claims.

I claim:

1. In the operation of superheater boilers initially operated under one condition and subsequently operated under a second condition, that improvement which consists in increasing the superheating surface without increasing the steam flow area through the superheater by inserting additional superheating units between one end of some of the original units and one of the superheater headers.

2. A superheater comprising inlet and outlet headers and a plurality of tubular superheating units, each secured at one end to one of said headers and adapted to be secured at its other end to the other of said headers, and means for detachably connecting some of said other ends with said other header comprising a plurality of tubular units forming additional superheating surface.

3. The combination with a superheater comprising inlet and outlet headers and a plurality of tubular superheating units, each secured at one end to one of said headers and at its other end adapted to be detachably connected to the other of said headers, of means for increasing the heating surface of said superheater without increasing the steam flow area therethrough comprising a plurality of tubular heating units detachably inserted between the last named ends of said first named units and said other header.

4. The combination with means defining a pass for combustion gases, of a superheater comprising inlet and outlet headers located outside said gas pass and heating means connecting said headers, said means comprising a plurality of multi-loop tubular superheating units located in the gas pass, each connected at one end to one header and having its opposite end located outside the gas pass and spaced from the other header, and a plurality of relatively short removable tubular elements one for each unit lying entirely outside said gas pass connecting the other header and the last mentioned ends of said units.

WILBUR H. ARMACOST.
